ABDOMINAL TRUSS AND SUPPORT

Max Kappner, Cincinnati, Ohio

Application March 22, 1933, Serial No. 662,117

1 Claim. (Cl. 128—96)

My invention relates to a truss or support particularly adapted for supporting the abdomen and relieving hernia and is an improvement on the invention shown and described in my co-pending application, Serial No. 621,075, filed July 6, 1932 for Abdominal truss and support.

Numerous supports and trusses have been made heretofore for the treatment of hernia and umbilical rupture as well as various types of abdominal supports. The conventional hernia trusses customarily used for the treatment of a hernia on both sides is comprised of an abdominal belt on the front of which are affixed in the proper places oval pads which press against the abdomen at the points where the hernia exists. It is common knowledge that a person wearing such a device has difficulty in maintaining the pads in their proper places, especially when working or exercising as at this time the pads slip and move out of position readily.

Frequently people troubled with hernia need an abdominal support. The present method of handling this situation requires the use of an abdominal support and an additional hernia truss. Consequently it has been found to be very inconvenient to wear a separate abdominal support and hernia truss because of the slipping of the truss pads.

In order to overcome the deficiencies and difficulties experienced with trusses and supports such as outlined above, I prefer to use the same type of abdominal shield as described in my co-pending application mentioned above. This shield is then encased with a leather or heavy cloth material having pockets on the inner side of the shield in which may be placed felt or other pads to increase the pressure at any desired point on the truss and support. While the shield itself may be initially constructed to fit any given condition it frequently becomes necessary after continued use to change its shape to give further pressure at a particular point. This may be accomplished quickly and easily by the insertion of further projecting pads in the pockets where they will be practically immovable and remain in the desired pre-determined positions.

In the particular embodiment of my invention selected for illustration:

Fig. 1 is a perspective of my device,
50 Fig. 2 is a plan view of the inner side of the shield properly encased, and

Fig. 3 is a section on the line 3—3 of Fig. 2.
Referring now to the drawing, the device is comprised of a shield 10 preferably constructed 55 of metal or some other substantially rigid mate-

rial having inwardly bulging portions 11 and 12 to press against the abdominal muscles to support them and to press inwardly against the points where hernia occurs. The central portion of the shield is depressed so as to prevent any pressure on the bladder, although the entire shield is so shaped as to have the general contour of the abdomen and fit snugly against it.

Around the shield 10 is sewed or otherwise secured a leather or cloth covering 13 having pockets 14 and 15 oppositely disposed and opening on the inner side of the shield and preferably towards each other. Any suitable felt or other types of pads may be placed within the pockets at any point where it is desired to raise the inner portion of the shield so as to create a greater pressure at one point than another. It can readily be seen that these pads will be compressed between the inside of the pocket and the bulging portions of the shield 11 or 12 and consequently will not slip or move about causing misplacement of the increased pressure area.

Any suitable belt such as 16 is provided with the device to fit around the waistline of the body to maintain the truss and support in proper position.

While the invention has been described above in its preferred form, it will be obvious that various changes and modifications can be made therein without departing from the spirit or scope thereof and it is therefore desired that only such limitations be imposed thereon as are necessitated by the prior art or specifically set forth in the claim.

An abnormal truss and support comprised of a rigid abdominal supporting shield transversely arcuate, integral hernia pads on the inner periphery of said shield and a non-rigid member enclosing said shield and constructed to form pockets between said casing material and the inner side of said shield, said pockets laterally opening towards each other.

MAX KAPPNER.
